UNITED STATES PATENT OFFICE.

FRANK H. SILVERTHORNE, OF NEW YORK, N. Y.

BOTTLE-STOPPER.

1,366,289.

Specification of Letters Patent. Patented Jan. 18, 1921.

Application filed April 16, 1917, Serial No. 162,282. Renewed February 3, 1920. Serial No. 355,955.

To all whom it may concern:

Be it known that I, FRANK H. SILVERTHORNE, a citizen of the United States, and resident of New York city, in the county of New York and State of New York, have invented certain new and useful Improvements in Bottle-Stoppers, of which the following is a specification.

My invention relates to a receptacle closure of the wedging type and particularly relates to such a closure designed to close bottles and other frangible and easily breakable parts.

In devices of this class now known it has been necessary either to provide the bottle with some particular form of neck, usually a rimmed construction, so as to accommodate the closure, or the closure had to be applied by machinery to effect a necessarily permanent sealing.

These particularly formed bottles are expensive to construct, and the machine secured closures are removed only with difficulty, and after removal are usually of no value for a subsequent closing.

Primarily the object of my invention is to provide a simple form of closure which can be quickly wedged into position on a plain rimmed bottle or other receptacle.

Another object of the invention is to provide a simple and inexpensive form of closure which can be readily forced on or demounted from the bottle by manual operation and which will hold simply by frictional tension and which will insure a secure closing of the bottle either temporarily or when packed for transit.

I attain this object broadly by providing a holding shell of non-elastic material and fitting a ring of compressible material in said shell. The bore of the ring at the bottle engaging end is somewhat reduced and proportioned so that, when the closure is forced onto the neck of the bottle, the wall at the engaged end tends to expand diametrically but is resisted by the incasing shell. The material forming the ring will then crowd toward the opposite end thus tending to distribute the ring material along the length of the shell and causing the bore to distort into a tight frictional engagement along the entire length of the bottle neck engaged thereby.

A further object of the invention is to provide a simple form of bottle closure for insuring the sealing not only of the liquid

pour-out passageway but also of the air inlet passageway in those receptacles which are provided with this plurality of fluid passageways opening through the throat of the bottle.

This object is attained simply by positioning a thin lining of compressible material between the inner edge of the ring and the top wall of the shell.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings—

Figure 1 is an axial sectional view through a bottle top showing a preferred embodiment of my invention in position thereon and

Fig. 2 is a similar view of the closure shown in Fig. 1 and detached from the bottle.

In the following description and in the claims, parts will be identified by specific names for convenience of expression but they are intended to be as generic in their application to similar parts as the art will permit.

In the drawings there is shown a bottle neck 3 on the top of which is mounted a cast porcelain pour-out member 4 fixed to the bottle by a securing flange 5. The pour-out is provided with a liquid pouring passageway 6 and an air-inlet passageway 7 usual in one known type of such constructions. This form of bottle end is provided so as to illustrate the application of the invention to a rimless receptacle, it being noted that the outer portion 8 of the pour-out is of general cylindrical form and relatively long, so as to provide a long engaging surface for the closure hereinafter described. The closure particularly forming the subject-matter of this invention is in the form of a top designed to telescopically fit the cylindrical portion of the receptacle and comprises an outer containing shell 9 preferably of metal and stamped to shape. The shell includes a cylindrical wall 10 and an end or top wall 11 integral therewith. Fitted within the shell and engaging the

cylindrical wall thereof is a ring 12 of some readily compressible material, such as cork, which ring is of a size to firmly engage the inner face of the wall 10 and is practically co-extensive therewith. This ring is provided with a centrally disposed bore 13 extending therethrough from end to end and having a diameter substantially equal to the diameter of the cylindrical part 8 engaged thereby.

10 This ring is particularly characterized by the fact that the lower end 14 thereof is of slightly greater thickness than the upper portion thereof, thereby to form the bore 15 into a frusto-conical form, with the small end disposed outwardly or at the bottom of the closure, as shown more particularly in Fig. 2. In this figure the thickness of the lower portion of the ring compared with 20 the upper portion has been purposely exaggerated in order to show that the diameter at the lower portion of the cap was slightly smaller than the diameter at the upper portion. In its commercially perfected form 25 there will be but very slight difference between the diameter at the upper end compared with the diameter at the lower end of the ring. A disk 15 of some suitable closing material, such as cork, is disposed between 30 the upper end of the ring and the adjacent top wall of the shell. The disk 15 is particularly designed to not only close the passageways 6 and 7 from the outside, but is 35 particularly of value to secure a complete closure between the passageways 6 and 7.

In operation it will be understood that 40 the closure is forced manually onto the cylindrical end of the receptacle, which action will tend to cause the material at the outer end of the ring to be compressed and distorted inwardly toward the upper portion adjacent the disk 15. The lower end of the ring 12 has a relatively lighter frictional 45 engagement with the cylindrical portion of the receptacle, than the upper end thereof. This construction has a tendency to distribute 50 the distorting strains on the lower end of the ring uniformly along the entire length of the bore, thus insuring a firm, frictional engagement between the closing member and the cylinder for substantially the entire length of the cork ring.

It has been found that this form of closure is possible of being inserted on and 55 withdrawn from its closing position by simple manual pressure and pull yet is peculiarly effective in hermetically sealing the bottle just as effectively as the usual cork stoppers.

60 While I have shown the described, and have pointed out in the annexed claims, cer-

tain novel features of my invention, it will be understood that various omissions, substitutions and changes in the form and details of the device illustrated and in its operation may be made by those skilled in the art without departing from the spirit of the invention.

Having thus described my invention, I claim:—

1. In a device of the class described, the combination with a cylindrical bottle neck, of a closure for said neck, said closure including a cylindrical containing shell surrounding the neck, and a ring of compressible material disposed between the neck and shell, one end of the bore of said ring being normally of a diameter slightly less than the diameter of said neck and the bore at another place normally having a 80 diameter slightly greater than the diameter at said end and approximately equal to the diameter of said neck, whereby the material of the ring at one place is of greater thickness than at another place and is designed 85 to be crowded toward said other place when the neck is forced into the bore of the compressible ring.

2. A closure including a cylindrical flange, and a sealing ring having a material length 90 compared with its diameter and fitted within said flange, the wall at one end of said ring being thicker than the opposite end and converging in thickness toward the opposite end thereby to form a frusto-conical 95 bore to the ring.

3. A closure comprising an outer cylindrical shell of non-elastic material and provided with an open end, and a compressible lining ring fitted within the shell the wall of 100 the ring adjacent the open end of the shell being of greater thickness than at the opposite end and forming a frusto-conical bore adapted to engage a bottle neck along the entire length of the bore.

4. A closure for receptacles including a receptacle engaging member in the form of a ring of compressible material and provided with a bore adapted to receive and frictionally engage the receptacle when the 110 member is telescoped thereon, one end of said bore being closed and the other opened said bore being smooth and having a diameter at its open end less than its diameter at the opposite closed end.

Signed at New York city, in the county of New York and State of New York, this fifth day of April, A. D. 1917.

FRANK H. SILVERTHORNE.
